UNITED STATES PATENT OFFICE.

CLARENCE L. ARMISTEAD AND SAMUEL F. BATES, OF SULLIVAN, MISSOURI, AS
SIGNORS OF ONE-THIRD TO JESSE R. FARRAR AND EDWARD E. MATHIAS, OF
LESLIE, MISSOURI

CASE.

Application filed July 26, 1923. Serial No. 653,947.

To all whom it may concern:

Be it known that we, CLARENCE L. ARMISTEAD and SAMUEL F. BATES, citizens of the United States, residing at Sullivan, in the county of Franklin and State of Missouri, have invented a new and useful Case, of which the following is a specification.

The device forming the subject matter of this application is a case, adapted primarily but not exclusively to contain eggs. The invention aims to provide a case of the kind mentioned which may be opened readily for packing and unpacking, and for purposes of display: and, further, to provide a case which may be used conveniently in connection with the machine for candling eggs shown in my co-pending application Serial No. 653,946, filed on the 26th day of July, 1923.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed; it being understood that, within the scope of what is claimed, changes in the precise embodiment of the invention shown can be made without departing from the spirit of the invention.

In the accompanying drawings:

Figure 1 shows in side elevation, a case constructed in accordance with the invention; Figure 2 is an end elevation; Figure 3 is a longitudinal section; Figure 4 is a section on the line 4—4 of Figure 3; Figure 5 is a section on the line 5—5 of Figure 3; Figure 6 is a perspective view showing one of the angular retainers.

The case forming the subject matter of this application is made of wood or any other suitable material and embodies a section 1 and a section 2. Each section comprises side walls 3 and 4 disposed at right angles to each other and connected to end walls 5 which are in the form of right triangles. Intermediate the ends of each section, a partition 6 is secured to the side walls 3 and 4, the partition 6 being in the form of a right triangle, and corresponding in shape to the end wall 5. Cleats 7 are

applied to the outer surfaces of the end walls 5 and extend along the diagonal edges of the said walls, the cleats being held in place by securing elements 8, engaging the end walls 5, the cleats on the sections 1 and 2 being in abutment, when the case is set up as disclosed in Figure 2. Hooks 9 are mounted on the cleats 7 of the section 2 and are adapted to engage with keepers 10 on the cleats 7 of the section 1, the hooks and the keepers constituting latches, and it will be understood that any sort of latch may be used at the place indicated. Keepers 11, preferably in the form of staples, are inserted through the walls 3 and 4 of each of the sections 1 and 2 into engagement with the partitions 6 and are located adjacent to the angles formed by the walls 3 and 4 of the sections 1 and 2. Angular retainers 12 are provided, the same including wings 14 having longitudinal slots 15. The angular retainers 12 extend about the angles defined by the walls 3 and 4 of the sections 1 and 2, as shown in Figure 4, the staples or keepers 11 being received in the slots 15 of the wings 14 of the retainers 12. Through the keepers 11 may be inserted securing members 16, such as cotter pins, seals or anything else which may be at hand. The end walls 5 of the section 2 are provided with projecting dowel pins 17, adapted to be received in recesses 18 formed in the edge of the walls 5 of the section 1.

The general construction of the device is such that the constituent sections 1 and 2 may be separated readily and when the sections are assembled, as shown for instance in Figures 2 and 5, relative movement between the sections 1 and 2 will be prevented owing to the presence of the dowel pins 17, the retainers 12 and the latches 9—10.

What is claimed is:

1. A receptacle of rectangular cross section, divided along a diagonal plane to form separable parts, angular retainers extended about the angles formed by cooperating walls of said parts, and means on said parts for engaging the retainers.

2. A receptacle of rectangular cross section, divided along a diagonal plane to form separable parts, transverse cooperating triangular partitions in said parts, keepers on said parts and engaged with the partitions,

and angular retainers cooperating with adjacent walls of said parts and engaged with the keepers.

3. A receptacle of rectangular cross section, divided along a diagonal plane to form separable parts having cooperating triangular end walls cleats along the inner edges of the end walls, latches connecting the cleats, and interengaging elements on 10 said parts, coacting to prevent relative slid-

ing movement between said parts in said diagonal plane.

In testimony that we claim the foregoing as our own we have hereto affixed our signatures.

CLARENCE L. ARMISTEAD.
SAMUEL F. BATES.

In presence of—
H. O. HOLLOW,
N. W. SHADDER.
